SIGNAL STORAGE TAPE MARKING
MACHINEKarl Höper, Berlin-Charlottenburg, Germany,
assignor to M. Erich Blume, Leipzig, GermanyApplication June 18, 1937, Serial No. 148,924
In Germany June 26, 1936

5 Claims. (Cl. 164—112)

The invention relates to tape perforating machines or the like which apply to a tape characters representing a message. Machines are known in which a reciprocating selector carriage moves over an intermediate pattern frame composed of elements which may be set by the selector to form a temporary pattern representing a line of a message. This pattern is subsequently translated with the aid of a detector or translator mechanism which is mounted on a second carriage and which cooperates with other machine elements to actuate the latter in accordance with the position of certain pattern elements, thereby impressing the desired characters on the tape. A machine of the aforesaid type is disclosed in the patent to Otto Wolters and Karl Höper, Patent No. 1,962,375, dated June 12, 1934.

The present invention has for its object to provide for a shiftable stop which is moved by the selector carriage to establish or mark the distance along the pattern frame which the selector carriage has traveled in setting up the elements corresponding to a line of the message to be transmitted, thereafter limiting the travel of the translator carriage to the distance required for translating the line of the message whereupon the stop returns with the translator carriage toward the original position until it meets again the selector carriage.

30 In accordance with the present invention the limit stop may be further arranged so as to be disconnected from the returning translator carriage when the stop on its return trip meets the selector carriage.

35 The invention may be employed generally for determining the travel of a translator carriage and it is immaterial in what manner the tape is marked, whether by punching, embossing, photographically, magnetically or in any other manner. The limit stop may therefore be a mechanical, electrical or magnetic device or the like.

The accompanying drawings represent an arrangement in which the limiting means comprise a mechanical stop. By way of example a machine is described which punches paper tape for the setting and casting of lines of printing type, as more fully set forth in the aforementioned patent. The arrangement is especially suitable for limiting the length of a line in machines having a typewriter-like keyboard and a stationary intermediate pattern frame, whose stationary but adjustable pattern elements are combined into character groups by actuation of corresponding keys. The individual pattern elements are returned to their normal position immediately upon the punching

of the corresponding character on the tape. While the first line is thus punched, the next line may be prepared by the renewed setting up or grouping of the intermediate pattern elements.

The embodiment of the invention illustrated in the drawings comprises a machine which punches holes into a tape, whereby prior to the punching operation adjustable intermediate elements are set up into a temporary pattern. After any corrections which may be necessary the pattern may be translated into the final characters independent of the said setting-up operation. To accomplish this, provision is made for a stop track with a movable stop for determining the length of a line. Movable mounted on this track is a selector carriage which is controlled to move step by step in accordance with the irregularly timed operation of the keyboard, and a detector or translator carriage, which is advanced by automatic means in regularly timed steps. The two carriages reciprocate in such a manner that the irregular keying and the rhythmic detecting or translating take place in a cycle which is not disturbed by mutual interference by virtue of the difference in speed between the relatively slow manual operation of the keys and the high speed automatic operation of the detector and punching mechanism.

The proper cycling of the various operating steps without mutual interference results from the alternations between the selector carriage and the translator carriage, both of which travel simultaneously alongside of the stop track, the former above and the latter below a pattern frame, being guided and advanced in the manner of a typewriter carriage. The forward speed of the translator carriage which is controlled by the mechanism is usually higher than the forward speed of the selector carriage, because the selection of the pattern elements depends upon the speed of the type-setter at the keyboard. The selector carriage is guided above and the translator carriage below the pattern elements which form a flat frame, by means of rolls which engage rails, the latter being fastened to the pattern frame.

45 In the accompanying drawings,

Figure 1 is a side view of a tape perforating machine embodying the invention,

Fig. 2 is a top view of the shiftable stop for limiting the travel of the translator carriage,

Fig. 3 is an end view, partially in section of the machine,

Figs. 4 to 8 inclusive, show certain details of Figs. 1 and 3 as will be explained more fully hereinafter.

Referring to the drawings, 1 designates a selector carriage by means of which the intermediate pattern members 9 are selected and actuated. The pattern is thereafter translated by the 5 detector or translator carriage 10 which translates and transmits the indications to the punching mechanism for producing the recording tape. The selector 1 is provided with rolls 6 and 7 by means of which it glides on the rail 2. Upon each 10 actuation of a key 28 on the keyboard the selector sets up by means of a series of hooks 8 the proper combination of intermediate elements 9, turning the respective elements to the position indicated at 9^a. With each stroke of a key the selector advances one notch or step.

The translator carriage 10 has a pair of rear rollers (not shown in the drawings), and a pair of front rollers 14, by means of which it glides on the rail 13. The rail 13 is slidingly mounted 20 in the diagrammatically indicated front wall 18 and rear wall 4 of the machine frame. A spring 26 biases the rail 13 toward the wall 18, the movement being limited by a stop 27. The translator carriage has mounted thereon a series of 25 bell crank levers 11 which are provided with releasable latches 64, the latter adapted to engage racks 65. The racks are connected to levers 66 which are oscillated by cams 69 and are biased by springs 67. One end of the levers 11 is adapted 30 to enter into gaps which are freed by the turning of the elements 9 and when they enter these gaps they transmit their motion through bell cranks 70-76 and spacers 77-83 to the punches of the punching mechanism for the tape 93.

35 The translator carriage is further provided with a bell crank lever 21 which is fastened thereon by a screw 22 and which during the forward travel is latched by a bell crank 20. This mechanism, when unlatched, lifts the spring biased bell crank 40 11 during the return stroke of the translator carriage 10 in order to avoid its becoming locked. The lever 20 is fastened to the carriage 10 by means of a screw 24.

On one side of the carriage 10 is a bar 12 which 45 is rotatably mounted at its ends in the frame of the machine and which at the beginning of a translating period is tilted by the depression of a lever 8. It thereby lifts the crank 21 through contact between the angle 12^a and the lever end 21^b. This permits the latch of lever 20 to engage 50 the catch 21^a and thus frees again carriage 10. Slidably mounted on the bar 12 is the line limiting stop 16. It may be moved forth and back either by the selector carriage 1 or by the translator carriage 10. A double ended lever 17 is fastened to the stop 16 by means of a screw 17^c. One end of the lever 17 is adapted to engage at 55 17^a a lug of carriage 1 which carries a screw 5. The lower end of lever 17 is provided with teeth 60 17^b. The carriage 10 is provided with a hooked leaf spring 19 which may engage by its hook the head of screw 17^c and thus draw the stop back to the starting position at the left. The leaf spring 19 is so proportioned that when the lever 65 17 engages the carriage 1 at 17^a it yields by bending backward and thus disengages the screw 17^c.

The apparatus functions as follows: If a text 70 is to be transferred with the described mechanism, which is assumed to punch a paper tape, the width of the symbols which are punched on the tape does not correspond to the width of the letters. As a result thereof the lines of symbols have varying lengths, even if they correspond to 75 the same printing length. It is of course also pos-

sible that lines have indentures, that is that they are not completely filled with characters.

In accordance with the invention the translator carriage travel is controlled by the automatically adjustable stop and is automatically declutched 5 from its motion imparting driving mechanism. For this purpose the stop 16 is at first carried forward by the carriage 1 and remains stationary when a line is completed, while the selector carriage 1 returns to its starting position. As soon 10 as a line is completed the detector carriage 10 is set in motion and operates until the pin 20^a of lever 20 engages lever arm 17^b. This frees the catch 21^a of lever 21 and lever 21 is again latched. At the same time the teeth 17^b of lever 17 engage 15 a toothed rack 15 which is fastened to the bar 13 and causes the latter to move with the stop 16. This permits the bar 25 to drop into a detent 20 25^a which action causes reversal of movement of carriage 10 and returns the latter to the starting position, the carriage being reciprocated by any suitable means.

When near the end of its forward travel the carriage 10 meets the stop 16, the spring 19 engages the screw head 17^c and the carriage 10 25 draws the stop backward until the carriage 1, which in the meantime may be actuated by the keyboard to prepare a new temporary pattern, engages the arm 17^a. This returns the stop 16 to the control of the carriage 1 and the cycle 30 is repeated. The alternate interaction between the two carriages 1 and 10 and the stop 16 is independent of the position of the carriages, so that the travel of the translator carriage is always limited to a distance corresponding to a line of 35 characters on the tape.

What I claim as new and desire to secure by Letters Patent is:

1. In a keyboard operated tape perforating machine or the like of the type having an intermediate pattern frame composed of elements which may be operated to form a temporary pattern representing a line of printing, in combination with tape perforating means, a reciprocable selector carriage, a reciprocable translator carriage, adapted to control said tape perforating means, and a pattern frame of said machine, a reciprocable adjustable stop device for said last named carriage to limit its forward travel, means to advance said device in accordance with the operation of certain elements of said pattern frame, said device including means to cause it to return with said last named carriage towards said first named carriage upon termination of the forward travel of said last named carriage. 40 45 50 55

2. In a keyboard operated tape perforating machine or the like of the type having an intermediate pattern frame composed of elements which may be operated to form a temporary pattern representing a line of printing, in combination with a reciprocable selector carriage, a reciprocable translator carriage, and a pattern frame of said machine, a reciprocable adjustable stop device for said last named carriage to limit its forward travel, means to advance said device in accordance with the operation of certain elements of said pattern frame, said device including means to cause it to return with said last named carriage towards said first named carriage upon termination of the forward travel of 60 65 70 75 80 85 90 95 100 said last named carriage, and coupling means to couple said device with said first named carriage during its forward travel, and to release it upon reversal of movement thereof. 105

3. In a keyboard operated tape perforating ma- 75

chine or the like of the type having an intermediate pattern frame composed of elements which may be operated to form a temporary pattern representing a line of printing, in combination 5 with a reciprocable selector carriage, a reciprocable translator carriage and a pattern frame of said machine, a reciprocable adjustable stop device for said last named carriage to limit its forward travel, means to advance said device in accordance with the operation of certain elements 10 of said pattern frame, said device including means to cause it to return with said last named carriage towards said first named carriage upon termination of the forward travel of said last 15 named carriage, coupling means to couple said device with said first named carriage during its forward travel, and to release it upon reversal of movement thereof, means to arrest said device upon cessation of forward movement of said first 20 named carriage and until the last named carriage contacts therewith to thereupon stop the forward travel of the latter and to initiate its return travel toward its starting position, and means to releasably attach said device to said 25 last named carriage to move therewith on said return travel and until said coupling means is again actuated.

4. In a keyboard operated tape perforating machine or the like of the type having an intermediate pattern frame composed of elements which 30 may be operated to form a temporary pattern representing a line of printing, in combination with a reciprocable selector carriage, a reciprocable translator carriage, and a pattern frame of said machine, a reciprocable adjustable stop device for said last named carriage to limit its forward travel, means to advance said device in accordance with the operation of certain elements 35 of said pattern frame, said device including means to cause it to return with said last named carriage towards said first named carriage upon termination of the forward travel of said 40 last named carriage, coupling means to couple said device with said first named carriage during its forward travel, and to release it upon reversal of movement thereof, means to arrest said device upon cessation of forward movement of said first named carriage and until the last named carriage contacts therewith to thereupon stop the forward travel of the latter and to initiate its return travel toward its starting position, and means to releasably attach said device to said last named carriage to move therewith on said return travel and until said coupling means is again actuated, said attaching means including means to release said device from said translating carriage upon engagement of said device by said selector carriage.

last named carriage, coupling means to couple said device with said first named carriage during its forward travel, and to release it upon reversal of movement thereof, a double arm lever mounted on said device, and a rack adapted to 5 engage one arm of said lever to thereby hold said device in a given position, the other arm of said lever being adapted to engage an abutment of said selector carriage to thereby release said one arm from said rack.

5. In a keyboard operated tape perforating machine or the like of the type having an intermediate pattern frame composed of elements which may be operated to form a temporary pattern representing a line of printing, in combination 10 with a reciprocable selector carriage, a reciprocable translator carriage and a pattern frame of said machine, a reciprocable adjustable stop device for said last named carriage to limit its forward travel, means to advance said device in accordance with the operation of certain elements 15 of said pattern frame, said device including means to cause it to return with said last named carriage towards said first named carriage upon termination of the forward travel of said last named carriage, coupling means to couple said device with said first named carriage during its forward travel, and to release it upon reversal of movement thereof, means to arrest said device upon cessation of forward movement of said 20 first named carriage and until the last named carriage contacts therewith to thereupon stop the forward travel of the latter and to initiate its return travel toward its starting position, and means to releasably attach said device to said 25 last named carriage to move therewith on said return travel and until said coupling means is again actuated, said attaching means including means to release said device from said translating carriage upon engagement of said device by 30 said selector carriage.

KARL HÖPER.
